JOSEPH HOFFAY, OF NEW YORK, N. Y.

PHONOGRAPH SOUND-BOX.

1,291,887.

Specification of Letters Patent. Patented Jan. 21, 1919.

Application filed July 10, 1916. Serial No. 108,346.

To all whom it may concern:

Be it known that I, JOSEPH HOFFAY, a citizen of the Republic of Mexico, and a resident of New York, in the county of New York and State of New York, have invented certain new and useful Improvements in Phonograph Sound-Boxes, of which the following is a specification.

My invention relates to phonograph sound boxes, and some of the objects thereof are to provide a sound box of very simple construction requiring little time and practically no skill in assembling; which insures the very desirable inward pressure on the diaphragm into normal contact with the strongest side of the box; which permits ready adjustment of this pressure; which provides a suspension for the stylus carrier at four points on the same axis; which provides a direct bearing of the stylus carrier on the box at two points instead of on lines or surfaces; which in one embodiment has the last named bearings on knife edges held against displacement; which provides means for lateral adjustment of the outer ends of the stylus carrier holding means; and which provides a noiseless insulation for the said holding means to prevent metallic sounds at the points of support thereof in the reproduction of a record.

My invention is fully described in the following specification, of which the accompanying drawings form a part, in which like characters refer to like parts in each of the views, and in which:

Figure 1 is a side elevation of a sound box constructed in accordance with my invention;

Fig. 2 is an edge view thereof on the axis of the stylus;

Fig. 3 is a fragmentary, enlarged, section taken on the line 3—3 of Fig. 1;

Fig. 4 is a view similar to Fig. 2 but with certain parts removed to show a detail of the construction;

Fig. 5 is a detached view of the stylus carrier and diaphragm arm;

Fig. 6 is a detached view of the stylus carrier holding means, with insulating means at the ends thereof, one of which is detached;

Fig. 7 is an enlarged fragmentary section taken on the line 7—7 of Fig. 1;

Fig. 8 is a similar view taken on the line 8—8 of Fig. 1;

Fig. 9 is a fragmentary view similar to Fig. 1 but showing a modification thereover; and

Fig. 10 is a section taken on the line 10—10 of Fig. 9.

Referring to the drawings, 11 represents the casing of a sound box containing a diaphragm 12 held between two resilient pads 13 and 14, the latter of which is against the integral and stronger side of the box 11 and which side is desired to serve as the main support for the diaphragm.

Secured to the diaphragm 12, as by a screw 15, is an arm 16 of yoke shape inserted into and secured within a stylus carrier 17 for the stylus 18 and provided with a hole 19 therethrough, for the passage of a carrier holding rod 20 of considerable length, relatively, and having its ends insulated or padded by means of rubber or other tube sections 21.

These ends are held beneath screws 22 in turn held in bifurcated brackets 23 in permanent connection with the casing 11 equidistant from the stylus carrier 17, and the rod 20 tends to force the said carrier against the edge of the sound box by reason of its resiliency, being sprung into its bowed shape, and the edge of the sound box is provided with a transverse V-shaped channel 24 in which the inner end of the stylus carrier rests.

In the form shown in Figs. 1 to 8, inclusive, the carrier 17 is provided with a curved knife edge 25 at its inner edge and which, because of the curve thereof and of the plane surfaces of the channel 24, bears against the casing 11 at two points, preferably in a groove 26 traversing said channel, Figs. 4 and 8, in order to prevent displacement of said knife edge transversely of the casing 11 in the vibratory movement of the carrier due to the stylus moving in the groove of a record, or because of the pressure exerted on said carrier by the rod 20 when the ends thereof are adjusted to bow said rod in plan view facing the edge of the casing 11 to force the diaphragm 12 against the pad 14.

The form shown in Figs. 9 and 10 is essentially the same as that described with the difference that the inner end of the carrier 17 is of semi-spherical form and no groove 5 26 is provided in the casing 11, the holder 20 forcing said carrier against the plane surfaces of the channel 24 but only at two points on the inner end of said carrier because of the rounded formation of the latter.

10 To adjust the tension of the rod 20 on the carrier 17 in the first form, the insulated ends of said rod are moved toward or from the upper or outer face of the sound box by means of the screws 22 in the brackets 23, or 15 manually by depressing said ends out of screw engagement, whereas in the form last described the carrier 17 may be forced, at its inner end, toward or from the outer face of the sound box to obtain the desired diaphragm tension or pressure, the uninterrupted surfaces of the channel 24 permitting such carrier adjustment. While the drawings disclose the possibility of adjustment of the ends of the rod 20 in this last described 20 form, it will be obvious that this is not imperative in view of the adjustability of the carrier transversely of the sound box.

In both forms, the bearing points of the carrier 17 and of the ends of the rod 20 are 30 on substantially the axis of rotation of said carrier, thereby permitting rocking movement of the latter by means of the stylus moving over a record, thus correspondingly affecting the diaphragm.

35 The assembling of the sound box is very simple and expeditious, the pads 13 and 14 and the diaphragm being placed within the casing 11, the detachable side of the latter assembled, the arm 16 secured to the diaphragm with the inner end of the carrier 17 in the channel 24, and the ends of the rod 20 passed beneath the screws 22, either previous to the connection of the arm 16 with the diaphragm or thereafter, in the latter 40 event the said screws 22 being removed from their supporting brackets 23 to permit the passage of the ends of the rod 20, the latter being soldered or otherwise permanently secured to the carrier 17.

45 In either form of construction the rod 20 tends to force the diaphragm inwardly, in the one form by the adjustment of the insulated ends, and in the other form by the adjustment of the carrier 17 in the channel 24 or, if desired, by said rod ends also, and the 50 resilient pads on the rod ends eliminate the possibility of metallic sounds at the bearing points thereof during the rendition of a selection on a record.

55 My sound box is very simple, very efficient, quickly assembled and adjusted, and is practically foolproof because of the few parts and the improbability of these parts being broken or deranged, and the relatively great length 60 of the rod 20 exerts a considerable influence

in the result because of the relatively great leverage thus provided and, thereby, of the considerable range of adjustment of the degree of pressure on the diaphragm.

While I have shown two preferred embodiments of the invention, I do not desire to limit myself thereto, but may make changes thereover provided that such changes do not depart from the spirit of the invention and come within the scope of the appended 75 claims.

Having fully described my invention, what I claim as new, and desire to secure by Letters Patent, is:—

1. A phonograph sound box, comprising 80 a casing, a diaphragm therein, a stylus-carrier in operative connection with said diaphragm, and means for holding said carrier against said casing, said carrier and said holding means having each two bearing points upon the casing in the axis of rotation of the carrier, whereby the carrier may be positioned relatively to the plane of the diaphragm independently of the holding 85 means. 90

2. A phonograph sound box, comprising a casing, a diaphragm therein, a stylus-carrier in operative connection with said diaphragm, and means for holding said carrier against said casing and for depressing said 95 diaphragm, said carrier and said holding means having each two bearing points upon the casing in the axis of the carrier, the bearing point of the carrier being adjustable with respect to the plane of the diaphragm 100 to enable said diaphragm to be readily given the proper amount of depression under the action of said holding means.

3. A phonograph sound box, comprising a 105 casing, a diaphragm therein, a stylus-carrier in operative connection with said diaphragm, a rod for holding said carrier against said casing and supports for the ends of said rod-forming bearings for said rod, said supports being positively connected to said casing, and said carrier and said rod having each two bearing points on the axis of rotation of the former, said bearing points being independently adjustable with respect to the plane of the diaphragm. 110 115

4. A phonograph sound box, comprising a casing, a diaphragm therein, a stylus carrier in operative connection with said diaphragm, a rod in operative connection with said carrier, and means for flexing said rod in one 120 direction to hold said carrier against said casing and in another direction for depressing said diaphragm.

5. A phonograph sound box, comprising 125 a casing, a diaphragm therein, a stylus carrier in operative connection with said diaphragm, a rod in operative connection with said carrier, brackets on said casing adjacent the ends of said rod, and means in 130 said brackets for maintaining said rod in

- flexed condition for holding said carrier against said casing and for flexing said rod in another direction to rock said carrier to depress said diaphragm.
6. A phonograph sound box, comprising a casing, a diaphragm therein, a stylus carrier in operative connection with said diaphragm, a rod in operative connection with said carrier, means for holding the rod in flexed condition to hold said carrier against said casing, and resilient pads interposed between the ends of said rod and said rod holding means.
7. A phonograph sound-box, comprising a casing having a V-shaped transverse channel, a diaphragm in said casing, a stylus carrier in operative connection with said diaphragm and having bearings in said V-shaped channel, resilient means for holding said carrier against the walls of said channel, the carrier being adjustable to change the transverse relationship of said carrier and said resilient means to enable the latter to depress said diaphragm.
8. A phonograph sound-box, comprising a casing having a V-shaped transverse channel, a diaphragm in said casing, a stylus carrier in operative connection with said diaphragm, said carrier having a rounded inner end bearing against the sides of said channel at two points, and resilient means for holding said carrier against said casing, said carrier being adjustable along said channel to enable said resilient means to vary the pressure upon said diaphragm.
9. A phonograph sound box, comprising a casing having a V-shaped transverse channel in its edge intercepted by a groove parallel to the face of said casing, a diaphragm in said casing, a stylus carrier in operative connection with said diaphragm and provided with a rounded knife edge resting in said groove and bearing against said casing at two points, means for holding said carrier against said casing, and means for changing the transverse relationship of said carrier and said holding means to depress said diaphragm.
10. A phonograph sound box comprising a casing, a diaphragm in said casing, a stylus carrier having an operative connection with said diaphragm and a bearing upon said casing, a rod connected with said carrier and means arranged to hold said rod flexed in the direction to maintain said carrier upon its bearing and also in the direction to rock said carrier to depress said diaphragm, said rod being located approximately in the plane of the diaphragm.
11. A phonograph sound box comprising a casing, a diaphragm in said casing, a stylus carrier having an operative connection with said diaphragm and having a bearing upon said casing, and means for maintaining said carrier upon said casing comprising a single member tensioned in one direction with respect to said casing to hold said carrier upon its bearing, and in another direction to rock said carrier upon its bearing to depress the diaphragm, said member having bearings substantially in the axis of oscillation of said carrier when moving perpendicularly to said diaphragm.
12. A phonograph sound box comprising a casing, a diaphragm in said casing, a stylus carrier having an operative connection with said diaphragm and a bearing upon said casing, a rod for holding said carrier upon its bearing connected to said carrier and having bearings upon said casing upon which it may oscillate with said carrier, and vibration absorbing means between said rod and its bearings.
13. A phonograph sound box comprising a casing, a diaphragm in said casing, a stylus carrier having an operative connection with said diaphragm and a bearing upon said casing, a rod for maintaining said carrier upon said bearing connected to said carrier and tensioned in directions substantially normal to each other, means for maintaining said rod in tensioned condition comprising connections to the casing, and vibration absorbing means between said rod and said connections.
14. A phonograph sound box comprising a casing, a diaphragm in said casing, a stylus carrier having an operative connection with said diaphragm and a bearing upon said casing, a rod connected to said carrier and tensioned to press upon said carrier in directions to maintain it upon its bearing and to rock it about its bearing, and means for maintaining said rod in tensioned condition, comprising bearings for said rod upon which it may oscillate with said carrier, said bearings being located substantially in the axis of normal oscillation of said carrier upon its bearing.
15. A phonograph sound box comprising a circular casing, a diaphragm in said casing, a stylus carrier having an operative connection with said diaphragm and a bearing upon said casing, a rod connected with said carrier and bent substantially in the arc of curvature of said casing to tension said rod to hold said carrier upon its bearing, and means for holding said rod in tensioned condition comprising bearings upon which said rod may oscillate with said carrier, said rod and carrier bearings lying substantially in a chord of said arc.
16. A phonograph sound-box comprising a casing, a diaphragm therein, a stylus-carrier in operative connection with said diaphragm, and means for holding said carrier against said casing, said carrier and said holding means having each two bearing points upon the casing, the mounting of said holding means being such as to permit oscil-

lation of the holding means with said carrier.

17. A phonograph sound box comprising a casing, a diaphragm therein, a stylus-carrier in operative connection with said diaphragm, and means for holding said carrier against said casing, said carrier and said holding means having each two bearing points upon the casing in the axis of the 10 rotation of the carrier, the mounting of the holding means being such as to permit oscillation of the holding means in the axis of rotation of the carrier.

18. A phonograph sound-box comprising

a casing having a transverse channel, a diaphragm in said casing, a stylus-carrier in operative engagement with said diaphragm, and means for holding said carrier against the walls of said channel.

19. A phonograph sound-box comprising a casing and a diaphragm in said casing, a stylus-carrier having an operative connection with said diaphragm and bearing upon said casing, and means for holding said carrier upon its bearing, said holding means held by said casing so that it may oscillate with said carrier.

JOSEPH HOFFAY.
